ATTORNEYS.

UNITED STATES PATENT OFFICE

ALFRED SCHMIEDER, OF MASPETH, NEW YORK

SCREW CLAMP

Application filed January 18, 1930. Serial No. 421,659.

My invention relates to improvements in means for clamping parts in position to facilitate the securing or working thereof, such as in the art of woodworking, and the same 5 has for its object to provide a simple, efficient and reliable device which is readily manipulated and secured in position to exert a clamping action along a plurality of lines of direction or at a plurality of points.

Another object of the invention is to provide a device of the character specified in which certain of the clamping components thereof are capable of being relatively moved to exert conjointly a third clamping action 15 along a line of direction extending transversely relative to the lines of direction of said clamping components.

Another object of the invention is to provide a device of the character specified in 20 which an attachment may be readily connected to a pair of clamps for causing positive movement thereof towards each other to exert a clamping action along a line of direction extending transversely relative to the 25 lines of direction of the individual clamps.

Other objects will in part be obvious and in part be pointed out hereinafter.

In the accompanying drawings:

Figure 1 is a perspective of one of the 30 clamps of the device constructed according to and embodying my said invention;

Fig. 2 is a plan of the device;

Fig. 3 is an elevation with parts broken away and parts in section; and

Fig. 4 is a section on the line 4-4 of Fig. 2.

Referring to the drawing the clamping means includes a pair of clamps 10 and 12, each comprising a standard 14 having a lower arm 16 secured thereon and upper arm 18

40 slideable thereon. The outer end of lower arm 16 is provided with a universally swiveled abutment 20 adapted to engage a piece or member to be clamped and the outer end of the upper arm 18 is provided with a

45 screw 22 threaded therethrough and having a universally swiveled abutment 24 cooperating with the abutment 20. The two clamps 10 and 12 are substantially alike in construction.

50 The clamps 10 and 12 are connected to-

gether by means 26 for moving the clamps toward each other to conjointly exert a clamping action along a transverse line. The connecting means 26 includes a pair of arms 28 and 30 preferably provided with hooklike 55 or slotted end portions 32 and 34 adapted to embrace the standards 14 to extend laterally towards each other and secured to the standards by the set screws 36. The members 28 and 30 are pivoted together at their inner 60 ends as indicated at 38.

Each member 32 and 34 is provided with a pair of rearwardly extending ears or brackets 40 between which are swiveled the nuts 42 and 44 upon vertical axes. A threaded actuating member 46 meshes with the nuts 42 and 44, the member 46 comprising preferably left hand and right hand threads as indicated at 48 and 50 so that the device may be more quickly clamped by means of the crank 52. 70

The abutments 20 and 24 are preferably roughened or ribbed as indicated at 54 to prevent the clamp from slipping over the work during the transverse clamping action.

In operation, the actuating means 26 are 75 readily secured to the clamping components 10 and 12 by engaging the slotted portions 32 and 34 with the standards 14 and securing the same by set screws 36 after being slidably adjusted thereon. The clamping components 80 10 and 12 are then engaged with the pieces of work by adjustment of the screws 22. By rotating the screw 46 the clamping components 10 and 12 move towards each other on pivot 38 without danger of slipping relative 85 to the work to exert a third clamping action along a transverse line and cause the pieces to be firmly pressed into engagement with each other at the contiguous edges thereof.

In my invention the clamping components 90 10 and 12 therefore form conjointly a third clamping component, thereby rendering the device more universal and flexible and enlarging the usefulness thereof.

Further, the clamping components 10 and 95 12 are connected by a plurality of parallel connections, one of which is pivotal and the other of which is the transversely extending actuating screw.

My device may be readily manipulated and 100

secured in position, and provides three different clamping. The working or securement of the pieces is thereby greatly facilitated and the device may be employed in connection with types of work for which the individual clamps 10 or 12 are inadequate, thereby providing a device having an enlarged range of usefulness, and particularly in connection with the fabrication of veneered articles, the gluing of various joints, and the working upon curved surface.

Having thus described my invention what I claim and desire to secure by Letters Patent is:

- 15 1. A device of the character described comprising a pair of clamps including standards and relatively adjustable clamping members thereon, members slidably adjustable longitudinally of said standards, each having rearwardly and laterally extending arms, the lateral arms being pivotally connected together at the contiguous ends thereof, and means cooperating with the rearward arms for swinging said clamps relative to each other.
- 20 2. A device of the character described comprising a pair of clamps including standards, arms relatively slidable on said standards, and clamping members at the outer ends of said arms relatively adjustable thereon, laterally and rearwardly extending arms on each standard between said arms, the lateral arms being pivoted together at the contiguous ends thereof, and means coacting with the rear arms for swinging said clamps about the pivot.
- 25 3. A device of the character described comprising a pair of clamps including standards, arms relatively slidable on said standards, and clamping members at the outer ends of said arms and relatively adjustable thereon, and an attachment for connecting said clamps for pivoted movement, including portions slidably engaging the standards for adjustment longitudinally thereof, arms extending laterally from said portions towards each other and pivotally connected at the contiguous ends, arms extending rearwardly from said portions, and means coacting therewith for swinging said clamps.
- 30 4. A device of the character described comprising an attachment for swinging clamps towards each other to exert a third clamping action including a pair of members, each having angularly disposed arms, and a portion intermediate said arms, said portions being adapted to engage the standards of the clamps for sliding adjustment longitudinally thereof, certain of said arms extending towards each other and pivotally connected, and means coacting with the remaining arms for swinging said members relative to each other.
- 35 5. A device of the character described comprising a pair of clamps including standards, slotted members on said standards, each having rearwardly and laterally extending arms,

the lateral arms being pivotally connected together at the contiguous ends thereof, swiveled members carried by the rearward arms, and an actuating screw connecting said swiveled members and meshing with certain of said swiveled members.

6. A device of the character described comprising a pair of clamps including standards, slotted portions detachably engaging said standards and each having rearwardly and laterally extending arms, the lateral arms being pivotally connected together, swiveled nuts carried by the rearward arms, and an actuating screw having reversely directed threaded portions meshing with said nuts.

7. A device of the character described comprising a pair of members having slotted portions for slidably engaging the standards of a pair of clamps for adjustment longitudinally of the standards, arms extending laterally from said slotted portions and connected together for pivotal movement, rearwardly extending brackets on said slotted portions, swiveled members on said brackets, and a threaded actuating member connecting said swiveled members and meshing with certain of said swiveled members.

8. A device of the character described comprising a pair of clamps including standards and relatively adjustable clamping members thereon, and members slidably adjustable longitudinally of said standards, each member having lateral portions and portions rearwardly thereof, the portions of one set being connected together for pivotal movement, and the portions of the other set having an actuating connection therebetween.

9. A device of the character described comprising a pair of clamps including standards, arms relatively slidable on said standards, and clamping members at the outer ends of said arms relatively adjustable thereon, and lateral and rearward portions on each standard between said arms, the portions of one set being connected together for pivotal movement, and portions of the other set having an actuating connection therebetween.

10. A device of the character described comprising a pair of clamps including standards, arms relatively slidable on said standards, and clamping members at the outer ends of said arms and relatively adjustable thereon, and an attachment for connecting said clamps for pivotal movement, including members slidably engaging the standards for adjustment longitudinally thereof, and portions projecting laterally and rearwardly from said last named members, the projecting portions of one set being connected together for pivotal movement, and the portions of the other set having an actuating connection therebetween.

11. A device of the character described comprising a pair of clamps including stand-

ards and clamping members slidably engaging said standards, and an actuating attachment including portions slidably engaging said standards for adjustment thereon relative to said clamping members, spacing means pivotally connecting said portions, and an actuating connection between said portions in spaced relation to said spacing means.

12. A device of the character described comprising an attachment for swinging clamps towards each other to exert a third clamping action including members adapted to engage the standards of the clamps for sliding adjustment longitudinally thereof, spacing means pivotally connecting said members, and an actuating connection between said members in spaced relation to said spacing means.

13. A device of the character described comprising an attachment for swinging clamps towards each other for exerting a third clamping action, including members adapted to engage the standards of the clamps for sliding adjustment longitudinally thereof, portions thereon pivotally connecting said members, other portions thereon in spaced relation to the first named portions, and an actuating connection between said last named portions.

30 In testimony whereof, I have signed my name hereto.

ALFRED SCHMIEDER.
